TUNING INDICATOR

Kurt Emde, Itasca, Ill., assignor to Zenith Radio Corporation, Chicago, Ill., a corporation of Illinois

Application February 24, 1941, Serial No. 380,339

5 Claims. (Cl. 250—14)

This invention relates to tuning indicators, and more particularly to tuning indicators for radio receiving apparatus employing manually adjustable tuning means and a loud speaker.

The principal objects of the invention are to provide a simple and efficient construction of the tuning indicator mechanism; to so arrange it as to render it easily accessible for inspection and adjustment; to arrange for a highly desirable location of the speaker within the casing of the apparatus for acoustic effects; to provide a conveniently placed, easily readable, large-scale tuning dial; to locate the tuning indicator with respect to the loud speaker so as to considerably reduce the space required therefor within the casing of the apparatus and so that the tuning dial and speaker openings may be associated in the front of the casing of the apparatus to economize space therein, whereby the apparatus may be more compactly arranged and enclosed, if desired, and whereby the efficiency of both the tuning indicator and the loud speaker may be improved; and to arrange for an improved symmetrical and artistic design of the radio cabinet or casing. These and other objects of the invention and advantages of the construction will appear from the following description.

In the drawings,

Figure 1 is a front elevational view of a radio receiving set embodying my improved tuning indicator, illustrating the advantageous arrangement of the tuning dial and speaker openings in the front of the casing of a small table model receiver and indicating the relative arrangement of the principal parts of my device with respect thereto by dotted lines;

Figure 2 is a fragmentary, horizontal sectional view, upon a slightly enlarged scale, taken upon the line 2—2 of Figure 1;

Figure 3 is a front elevational view, partly broken away, taken upon the line 3—3 of Figure 2, illustrating the arrangement of my tuning indicator with respect to the loud speaker; and

Figure 4 is a fragmentary, vertical sectional view, also upon a slightly enlarged scale, taken upon the line 4—4 of Figure 1, further illustrating the compact arrangement of my tuning indicator with respect to the loud speaker and with respect to the casing of the receiver, the convenient arrangement of the tuning dial and pointer to provide an easily readable tuning scale, and the economy in space required in the front of the casing for the tuning dial and speaker openings.

The particular design of the casing herein

shown is not a part of this invention, but it embodies certain features of casing construction which are and which I shall describe and claim. It is to be understood that, while the invention is herein illustrated as applied to a small radio receiving set, known as a "table" model, it is not in any sense limited thereto. It may be just as well and advantageously applied to larger radio receiving sets, known as floor or "console" models, and it is particularly suitable for use with tunable radio apparatus which may be associated and encased with other apparatus, such as, for example, radio-talking-machine combinations and radio-television receiving sets.

In the designing and construction of radio receiving sets, it has been the usual practice to arrange the tuning indicator and the loud speaker in each set a considerable distance apart and to employ entirely separate openings therefor in the casing of the set. In the floor or "console" models, the tuning indicator is generally located, for obvious reasons, in the upper portion of the cabinet, and the speaker in the lower portion thereof, while, in the smaller or "table" models, the tuning indicator and the loud speaker are usually arranged back of separate openings located near the opposite ends of the front of the casing. It has been realized that neither of these arrangements of the speaker affords the most desirable acoustic effects. In the "console" models, the loud speaker should be a considerable distance from the floor of the room in which the receiver is used, preferably on a level with the ears of the listener, and in the "table" models, the speaker should be as evenly spaced as possible from the walls of the small casing, preferably in the middle thereof, to obtain the best results.

Aside from arranging for better placement of the speaker, various constructions have been devised which propose space economy by arranging the tuning indicator within the hollow of the speaker-cone and positioning the indicator-dial so that it occupies or may be viewed through the speaker opening in the casing, but, so far as I am aware, no satisfactory arrangement of this character has been adopted and used. Popular demand requires a full-view tuning indicator dial sufficiently large and clearly defined to be satisfactorily readable, regardless of the size of the receiving set and regardless of the size of the loud speaker, and it has been found that such a dial may not be positioned to occupy or be viewed through the speaker opening in the casing without materially interfering with the speaker output, especially where a small speaker

and a correspondingly small speaker opening are employed.

In the arrangement herein provided, it will be observed that the speaker is centrally positioned in the casing; that the speaker opening is in the form of a circular grille, the diameter of which is equal to that of the speaker-cone; and that the tuning dial is arranged closely above and around the entire upper half of the rim of the grille, thereby providing, without interfering with the output of the speaker, a conveniently positioned, easily readable, semi-circular scale, the division markings or graduations of which may be satisfactorily spaced to provide for accurate tuning adjustments.

Referring, first, to Figure 1 of the drawings, 1 indicates the outer casing of a small table model radio receiving set; 2, the knob for manually operating the usual or any desired form of off-and-on switch and volume control; 3 the knob for manually operating the tuning means and tuning indicator to be presently described; 4, the circular speaker grille; 5, the opening in the casing 1 through which the indicator dial and pointer are viewable; 6, the indicator dial; and 7, the indicator pointer. The upper semi-circular rim-member 8 of the grille 4 is paralleled by the 180-degree tuning scale 9 which is traversed by the pointer 7. Attention is directed to the central and symmetrical arrangement of these parts in the front of the casing and to the large speaker opening and tuning scale provided by such arrangement.

In Figures 2 to 4, inclusive, the chassis is indicated at 10. The loud speaker 11 is secured upon the forward central portion of the chassis by screws 12 (Figure 4), and the manually adjustable tuning means, the variable condenser 13, is secured upon the rightward end part of the chassis by bolts 14 passed through spacer-cushions 15 (Figure 3). The top and front vertical wall of chassis 10 is preferably recessed, as indicated at 16, to receive the lower sweep of the bell-frame 17 and cone 18 of speaker 11. A vertically arranged baffle-plate 19 completely covers opening 5 in casing 1 (see Figures 2 and 4) and is formed with a downwardly projecting bib 20 which extends around and closely back of the lower portion of speaker grille 4. A circular recess 21 is formed in baffle-plate 19 and the back of this recess is cut away to leave a circular rim 22 and four radial spider-arms 23 joined at the center of the recess and supporting a stud 24. Baffle-plate 19 is secured in position by screws 25 passed through the rim of bell-frame 17, the rim-ring 26 of cone 18, and the circular rim 22 of recess 21.

Tuning scale 9 is arranged upon the face of baffle-plate 19 as a semicircle scribed from stud 24. As herein shown, the scale 9 is displayed upon a card which is held in position upon the face of baffle-plate 19 by means of rivets 27, but it is to be understood that this arrangement is illustrative only and may be varied in many ways without departing from the spirit and scope of my invention. The scale may be etched upon, pressed in or perforated through the baffle-plate, if desired, or the card may be of translucent material and illuminated in various well-known ways, the important point being that it should be accurately arranged with relation to stud 24, so that it may be properly traversed by pointer 7 which is pivotally supported upon the stud. It will be noted that the axis of stud 24 is coincident with that of the circular speaker grille 4, and that

the semicircular tuning scale 9 parallels the semi-circular rim of the upper half of said grille.

Indicator pointer 7 is fixed upon the hub 28 of a spoked and grooved pulley 29, which hub is rotatably mounted upon stud 24 and retained thereupon by means of a spring-clip 30 removably snapped into an annular groove (not shown) in the forward end-part of the stud. A second grooved pulley 31, similar in size to pulley 29, is fixed upon the rotatable shaft 32 of the variable condenser 13, the rotor and stator plates of which are indicated at 33 and 34, respectively, in Figure 2. A short shaft 35 is rotatably supported in any suitable manner upon or within chassis 10 to project forwardly from the front wall thereof through the front of the casing 1, and knob 3 is fixed upon the forward end-part of the shaft whereby it may be manually rotated. Shaft 35 is provided with an annular groove 36, which is in tractive alignment with pulleys 29 and 31, and a cord belt 37 connects the two said pulleys with each other and with the shaft. As shown in Figures 2 and 3, the lower reach of belt 37 extends from pulley 31 to pulley 29 through opening 38 in the cylindrical wall of recess 21, the upper reach is brought down through opening 38 and given a turn or two around shaft 35 and thence back to pulley 31, the ends of the belt being joined together by a spiral takeup spring 39.

The single-belt operation of the rotor of the variable condenser 13 and of the indicator pointer 7 by the turning of knob 3 is too obvious to require description, but it may be noted that, since pulleys 29 and 31 are of the same size, adjustments of the rotor-plates 33 of the 180-degree variable condenser 13 will be correspondingly indicated by the pointer 7 upon the 180-degree tuning scale 9, and the small diameter of shaft 35, as compared with the diameters of pulleys 29 and 31, will provide what is known as a vernier adjustment of the tuning means and the tuning indicator.

In the claims the term "speaker grille" is not to be understood as limited to the particular form of speaker opening herein shown, but is to be broadly construed as including any construction, method, or material used for disguising or covering speaker openings and concealing parts otherwise open to view.

I claim:

1. In tunable radio apparatus, a casing, a wall comprised in said casing provided with a speaker grille and an adjoining tuning indicator view opening, a chassis within said casing, a speaker fixed upon said chassis directly back of the speaker grille in said wall, a tuning scale supported upon said chassis in position to be viewed through the tuning indicator view opening in said wall, movable indicating means mounted upon said chassis in front of said speaker and extending to traverse said scale upon movement thereof, said indicating means being partially concealed by the speaker grille in said wall and partially exposed to be viewable with said scale through the tuning indicator view opening in said wall, tuning means fixed upon said chassis apart from said speaker, and manually adjustable means operatively connected with said tuning means and with said indicating means acting upon adjustment thereof to effect the adjustment of said tuning means and indicate such adjustment by the positioning of said indicating means with respect to said tuning scale.

2. In tunable radio apparatus, a casing, a wall

comprised in said casing provided with a circular speaker grille and an adjoining tuning indicator view opening, a chassis within said casing, a speaker fixed upon said chassis directly back of the speaker grille in said wall, a semi-circular tuning scale supported in position upon said chassis to be viewed through the tuning indicator view opening in said wall, the axis of said scale being coincident with the axis of the circular speaker grille in said wall, an indicator pointer pivotally mounted upon said chassis in front of said speaker, the pivotal axis of said pointer being coincident with the axis of the circular speaker grille in said wall and the free end of said pointer traversing said semi-circular tuning scale, and adjustable tuning means fixed upon said chassis apart from said speaker and said pointer and operatively connected with said pointer.

3. In tunable radio apparatus, a chassis, a speaker and tuning means independently supported upon said chassis, a speaker-cone and a bell-frame comprised in said speaker, said bell-frame having a circular rim by which the outer rim of said speaker-cone is supported, a baffle-plate having a circular speaker opening therein and secured about said opening to the rim of said bell-frame, an arm extending from the rim to the center of said opening, a stud fixed upon said arm in the center of said opening, a semi-circular tuning scale carried by said baffle-plate in position thereupon to constitute said stud as the axis of said scale, a pointer pivotally mounted upon said stud with its free end traversing said scale, and manually adjustable means operatively connected with said tuning means and with said pointer.

4. In tunable radio apparatus, a chassis, a speaker and tuning means independently supported upon said chassis, a baffle-plate secured to

5

said speaker, a stud fixed upon said baffle-plate in front of said speaker, an arcuate tuning scale carried by said baffle-plate in position to constitute said stud as the axis of said scale, a pointer and a pointer driving pulley fixed with respect to each other and rotatably mounted upon said stud with the free end of the pointer traversing said scale, a rotatable adjusting shaft comprised in said tuning means, a driving pulley fixed upon shaft having the same diameter as said pointer driving pulley, a manually adjustable shaft rotatably supported upon said chassis, and means operatively connecting said pulleys with each other and with said shaft.

5. In tunable radio apparatus, a casing, a wall comprised in said casing having a speaker opening and a tuning indicator view opening adjoining each other in the middle of said wall, a chassis within said casing, a speaker fixed upon said chassis directly back of the speaker opening in said wall, a baffle-plate supported closely back of and parallel with said wall, extending beyond the boundaries of the aforesaid openings therein, and having a recess in alignment with the speaker opening in said wall, at the back of which recess said baffle-plate is secured to said speaker, a speaker opening in the back of the recess in said baffle-plate, a stud supported upon said baffle-plate within the recess therein, an arcuate tuning scale upon said baffle-plate viewable through the view opening in said wall, a pointer rotatably mounted upon said stud with the free end thereof traversing said scale and also viewable through the view opening in said wall, and adjustable tuning means fixed upon said chassis apart from said speaker and said pointer and operatively connected with said pointer.

KURT EMDE.
